Primary Examiner — Marissa J Cash*Assistant Examiner* — Jessie Anne E Touart(74) *Attorney, Agent, or Firm* — Bodman PLC(57) **CLAIM**

The ornamental design for a weapon sight, as shown and described.

DESCRIPTION

FIG. 1 is a front top right perspective view of a weapon sight.

FIG. 2 is a rear top right perspective view thereof.

FIG. 3 is a top view thereof.

FIG. 4 is a back side view thereof.

FIG. 5 is a front side view thereof.

FIG. 6 is a right side view thereof; and,

FIG. 7 is a left side view thereof.

The broken lines in the figures illustrate portions of the weapon sight and form no part of the claimed design.

1 Claim, 7 Drawing Sheets(56)
